UNITED STATES PATENT OFFICE.

CHARLES LIPPINCOTT AND JAMES PATTERSON, OF PHILADELPHIA, PA.

DESIGN FOR SODA-WATER APPARATUS.

Specification forming part of Design No. 6,543, dated April 1, 1873; application filed March 19, 1873.

To all whom it may concern:

Be it known that we, CHARLES LIPPINCOTT and JAMES PATTERSON, both of the city and county of Philadelphia, State of Pennsylvania, have invented a Design for a Soda-Water Apparatus, of which the following is a specification:

The nature of our design is clearly illustrated by the figure in the accompanying drawing.

The apparatus is hexagonal in shape, and has at each of its six corners a vertical column, *a*, the bases of the latter being joined by a molding, *b*, and a molding, *d*, extending horizontally around the apparatus, and separating each of the sides of the same into two panels, each of which has the interior ornamentation shown. The capitals *e* of the columns *a* are surmounted by small vases or urns *f*, and each of the sides of the apparatus is capped by a

heavy molding, *g*, surmounted by a pedestal, on which urns and statues are arranged alternately, as shown. At the rear of the statues is a glass-covered fountain, *h*, but one of which is shown in the present instance. The apparatus has the usual draft-tubes and syrup faucets.

We claim—

The design for a soda-water apparatus, substantially as described, and as illustrated in and by the accompanying drawing.

In testimony whereof we have signed our names to this specification in the presence of two subscribing witnesses.

CHAS. LIPPINCOTT.
JAMES PATTERSON.
